UNITED STATES PATENT OFFICE.

JAMES C. POTTER AND JOHN JOHNSTON, OF PAWTUCKET, RHODE ISLAND, ASSIGNORS TO POTTER AND JOHNSTON MACHINE COMPANY, OF PAWTUCKET, RHODE ISLAND, A CORPORATION OF RHODE ISLAND.

LATHE.

SPECIFICATION forming part of Letters Patent No. 735,583, dated August 4, 1903.

Application filed January 7, 1901. Serial No. 42,364. (No model.)

To all whom it may concern:

Be it known that we, JAMES C. POTTER, a citizen of the United States, and JOHN JOHNSTON, a subject of the King of Great Britain, 5 both residing at Pawtucket, in the county of Providence and State of Rhode Island, have invented a new and useful Improvement in Lathes, of which the following is a specification.

10 This invention has reference to the class of lathes in which the work is supported and rotated by the head-stock spindle and the tools are supported on a tool-slide which carries the tools forward and backward to operate on the work.

15 The invention consists in the peculiar and novel construction and combination whereby the tool-slide is operated by a lever, the throw of which may be adjusted and the 20 travel of the tool-slide varied, as will be more fully set forth hereinafter and more particularly pointed out in the claims.

25 In a lathe of the nature described the length of the travel of the tool-slide requires 25 to be changed as the nature of the operations of the tools may require. To secure the best results, the speed of the feed of the several tools should also be varied.

30 The object of this invention is to so construct the tool-slide-operating mechanism that the length of travel of the tool-slide may be accurately and conveniently adjusted.

35 Figure 1 is a longitudinal sectional view of the tool-slide end of a lathe, showing the lever for operating the tool-slide and the operating mechanism. Fig. 2 is a transverse sectional view, on an enlarged scale, of the tool-slide end of the lathe, showing the mechanism for adjusting the throw of the lever 40 and the length of the travel of the tool-slide. Fig. 3 is a horizontal sectional view of the adjusting mechanism. Fig. 4 is a detail view showing the rack-and-pinion connection of the adjusting mechanism.

45 Similar letters of reference indicate corresponding parts in all the figures.

In the drawings, A indicates the frame or standard on which the operative parts of the lathe are supported. The frame A is pref-

erably formed with inclined and closed sides 50 and ends to inclose and protect the operative mechanism, suitable doors being provided to give the required access to the interior of the frame. The tool-supporting slide B is supported on ways formed on the upper part of 55 the frame A. A turret C is usually used on this class of lathes, rotatably supported on the tool-slide B and adapted to present a series of tools successively to the work.

60 In the rear end of the tool-slide B the longitudinal slot b and below this the ways b² are formed to fit the bracket b'. The clamping-bolt b⁵ extends through the slot b and serves to clamp the bracket b' to the tool-slide. The screw-spindle b³ is journaled in 65 the tool-slide and provided with a wrench-head at one end. The screw-spindle b³ extends through and is in screw-thread engagement with the bracket b'. The link b⁴ is pivotally connected with the preferably slotted 70 bracket b', as is shown in Fig. 2. The other end of the link b⁴ is pivotally connected with the upper end of the lever D, the lower end of which is supported on the rock-shaft d, journaled in the sleeves d' d', secured in 75 the lower part of frame A. The lever D has the ways d² d² extending lengthwise, in which the slide d⁸, inclosing the wrist-pin d⁴, may slide. The wrist-pin d⁴ is secured to the carriage d⁵, supported in the ways d⁶, secured to 80 or forming part of the gear d⁷, which is provided with the trunnion d⁸, journaled in the bearing d⁹, secured to the frame A.

85 The carriage d⁵ has the groove d¹⁰ of T-shaped cross-section, in which the head end of the bolt d¹¹ is inserted. The rack-bar d¹² is secured to the carriage and engages with the pinion d¹³ on the sleeve d¹⁴, which extends through the axis of the trunnion d⁸ and is provided at its outer end with the arm d¹⁵, 90 by which the sleeve d¹⁴ and pinion d¹³ may be turned to adjust the carriage d⁵ and the wrist-pin d⁴. The bolt d¹¹ extends beyond the end of the sleeve d¹⁴ and is screw-threaded. The nut d¹⁶ may be turned to draw the head 95 of the bolt onto the carriage d⁵ and the carriage against the gear d⁷ to hold the carriage in the adjusted position.

The index-plate d^{17} is secured by bolts d^{18} , as shown in Fig. 3, so as to rotate with the trunnion d^8 . A series of holes d^{19} , placed at predetermined distances apart near the periphery of the plate, serve to indicate the movement of the arm d^{15} and the adjustment of the carriage d^5 , and to secure the arm in the adjusted position the spring-pressed pin d^{20} enters one of the holes d^{19} . The tightening up of the nut d^{16} may be used to secure the arm d^{15} by causing the nut to bear on the hub of the arm, as is shown in Fig. 2. By this construction the tool-slide is moved toward the work at slow speed, gradually diminishing as the tool acts on the work toward the end of the forward movement of the tool-slide and is withdrawn at a much higher speed as the wrist-pin d^4 acts on the lever D during the return movement at points nearer the pivoted end of the lever than it does at the forward movement.

Power is imparted to the gear d^7 by the shaft E, which is driven from the head-stock. The worm e on the shaft E engages with the worm-gear e' . This gear is supported on a sleeve within which the shaft e^2 is supported. The pinion e^3 is secured to the shaft e^2 and engages with the gear d^7 , by which the mechanism for operating the tool-slide is operated. Between the worm-gear e' and the pinion e^3 is connected a speed-changing mechanism controlled by a series of dogs e^4 , adjustably secured to the disk e^5 , the shaft of which disk is driven from the shaft e^2 , so as to make one revolution during the series of reciprocations of the tool-slide required to perform the functions of all the tools used on one piece of work and to reproduce the same work on a series of pieces.

The particular construction of the speed-changing mechanism used forms no part of this present application. Said mechanism and the controlling means therefor are shown

and claimed in our application, Serial No. 42,365, filed January 7, 1901, and the same are 45 therefore not set forth in detail herein.

Having thus described our invention, we claim as new and desire to secure by Letters Patent—

1. The combination of a part to be moved, a lever, a wheel, a carriage slidably mounted on the wheel having a lever-engaging crank-pin, a shaft, connections between the latter and the carriage for sliding the carriage, a bolt passing through said shaft, and means whereby the bolt clamps the carriage to the wheel. 50

2. The combination of a part to be moved, a lever for reciprocating the same, a wheel, a carriage slidably mounted on the wheel, a 60 rack connected with the carriage, a pinion meshing with the rack, a sleeve extending axially through the wheel-hub on which the pinion is mounted, a bolt passing through the pinion-sleeve and engaging the carriage, and a nut on the bolt to draw the bolt, to clamp the carriage against the wheel and the carriage against the pinion. 65

3. The combination of a part to be moved, a lever for reciprocating the same, a wheel, 70 having a lever-engaging crank-pin, a shaft, gearing actuated by the shaft to shift the position of the crank-pin, a handle on the shaft for turning it, and a clamping-bolt and nut for fixing the position of the crank-pin, the 75 nut engaging the side of the shaft-handle to clamp it also.

In testimony whereof we have hereunto signed our names to this specification in the presence of two subscribing witnesses.

JAMES C. POTTER.
JOHN JOHNSTON.
